UNITED STATES PATENT OFFICE.

JOSEPH PRUSH AND ALVIN B. LANIGAN, OF BROOKLYN, NEW YORK.

CHOKE DETECTOR.

Application filed April 27, 1923. Serial No. 635,074.

To all whom it may concern:

Be it known that we, JOSEPH PRUSH and ALVIN B. LANIGAN, both citizens of the United States, and residents of the city of 5 New York, borough of Brooklyn, in the county of Kings and State of New York, have invented a new and Improved Choke Detector, of which the following is a full, clear, and exact description.

10 This invention relates to an improvement in detecting devices for folding machines, feeding machines and other machines used in the printing and allied trades and has for an object to provide an improved construction which will act to shut off the power from the machine immediately after any given sheet of paper has moved out of its proper registry.

15 Another object of the invention is to provide a detecting structure for folding machines, feeding machines and the like which acts on the rear edge of paper passing through the machine whenever the particular sheet of paper is moved out of its correct position according to the timing of the machine.

A further object of the invention is to provide an attachment which acts on the paper passing through the machine when the paper 20 is moved out of its correct position, regardless of whether the paper is crumpled or straight and when so acting causes the stoppage of the entire machine.

A still further object, more specifically, 35 is to provide a detecting mechanism including a moving arm designed to strike sheets of paper passing through the machine in case they are out of their correct position and a readily adjustable cam for connecting 40 the arm to the moving parts of the machine so as to readily time the movement of the arm to the movement of the paper passing through the machine.

In the accompanying drawings—

45 Figure 1 is a fragmentary top plan view of a folding machine of a well known type, together with an embodiment of the invention.

Figure 2 is a sectional view through Figure 1 approximately on line 2—2.

Figure 3 is a fragmentary sectional view similar to the mechanism shown at the right upper part of Figure 2 but with the detector arm in a lowered and detecting position.

55 Figure 4 is a view similar to Figure 3 but showing the arm in its extreme lowered

position which it assumes after the passage of each sheet of paper when the paper is in its correct position.

Referring to the accompanying drawings 60 by numeral, 1 indicates a folding machine designed to fold sheets or pieces of paper and in order to do so the sheets are fed from a given supply to the folding mechanism. The feeding mechanism and the folding 65 mechanism form no part of the present invention except in connection with the detecting and stop mechanism hereinafter fully described.

As indicated in Figure 1, the various 70 sheets of paper 2 are fed along by belts 3 to a given point and then the sheets of paper automatically move over onto the other belts 4 and finally onto the folding mechanism 5. It is very desirable and usually necessary 75 to have the sheets 2 fed correctly onto the folding mechanism in order that they may be properly folded and also in order that the machine will not become choked. If the sheets should become crumpled, they would 80 not be properly moved to the folding mechanism 5 and, consequently, the succeeding sheets would pile up and choke the machine unless the machine was stopped quickly.

In machines of this type, it is difficult 85 and almost impossible, for a workman to continually observe whether or not the various sheets of paper are in their respective correct positions as the machines often have more than one set of transporting belts 3 90 and 4 as indicated in Figure 2. Heretofore, attempts have been made to operate the stop motion mechanism but these attempts have been limited to means actuated by a crumpled paper, as for instance, the sheet 2' 95 (Figure 2.) Heretofore, small rods or arms extend over the belts 4 and when a crumpled sheet, similar to sheet 2', passes thereover, these arms are moved and the circuit is closed for shutting off the power to the 100 machine. This would occur even if the crumpled sheet was in its correct position. However, when a sheet moves diagonally through the machine or is out of position, these former detectors will not operate and, 105 consequently, the sheet will cause the machine to clog up to a greater or less extent.

In the present invention, means have been provided for immediately detecting a sheet when out of position whether crumpled or smooth. In the accompanying drawings, one embodiment of the invention has been

disclosed which has been applied to a well known type of folding machine but it is evident that it may be applied to other types of folding machines and other machines of a similar nature which feed the paper to a desired point.

As indicated in Figure 2, a pair of contacts 6 and 7 are provided, said contacts being connected through suitable wires 8 and 9 with the windings 10 of the magnetically operated number. A suitable source of current 11 is interposed in the circuit so that when the contacts 6 and 7 are in engagement, the magnet 10 will be energized and will shift the arm 12 to move it away from the contact members 13 and 14. These contact members form part of a circuit of the motor 15, which motor is connected in any desired manner with the machine 1 for driving the same. It will thus be seen that whenever the contacts 6 and 7 are closed, the motor 15 will be immediately disconnected from its source of power and, consequently, the machine will stop. Different forms of contacts 6 and 7 and associated parts might be provided without departing from the spirit of the invention but the arrangement shown in Figure 2 has proven satisfactory.

It will be noted that the contact 6 is connected with or formed integral with a small shaft 16 which is provided with an enlargement 17, which enlargement is struck by the shoe 18, which shoe is preferably a flat strip of spring metal easily moved and acting to give a comparatively large contact surface to the member 17. The contacts 6 and 7 and also the members 16, 17 and 18, are all mounted on an arm 19 which is rigidly secured to a fitting 20 and said fitting in turn is rigidly secured to a shaft 21 by a set screw 22 or other suitable means. The arm 19 is preferably of spring metal, though not necessarily so. An arm 23 is also rigidly secured to the shaft 21 in any desired manner, said arm 23 being pivotally connected with a link 24, which link in turn is connected with an auxiliary arm 23' rigidly secured to the shaft 25, which shaft carries an auxiliary arm 19' and parts identical with the parts carried by arm 19 but operating in connection with the transporting belts 26 instead of the transporting belts 4. The arms 23 and 23' are of the same length and, consequently, act together so that the arms 19 and 19' are swung simultaneously and for the same distance. The respective shafts 21 and 25 are journaled in suitable bearings in the machine 1 but driving mechanism is connected to shaft 21 only as the power is transmitted through the link 24 and associated parts to shaft 25. An arm or lever 27 is rigidly secured in any desired manner to shaft 21 and is pivotally connected at its outer end with a link 28,

which in turn is pivotally connected at 29 to lever 30, pivotally supported at 31 in any suitable manner. A retractile spring 32 continually acts on the lower section 30' of lever 30 to normally hold the arms 19 and 19' elevated as illustrated in Figure 2. An actuating rod 33 is pivotally connected at 34 to the lower section 30' of lever 30 and is provided with a fitting 35 at the end which is supplied with a forked 75 or yoke member 36 and with an anti-friction roller 37 journaled on a suitable pin 38. The roller 37 acts on the periphery of the cam 39 and as this cam is formed with an arc-shaped section 40 and a cam face 41, so the rotation of this cam will cause the lever 30 and associated parts to remain stationary for part of the revolution of the shaft 42 and to move for the remaining part of the revolution of shaft 42. When the cam 39 85 moves around until the cam face 41 approaches the roller 37, the spring 32 will begin to act and will cause said roller to follow the cam face 41 and, consequently, to cause the lever 30 to swing in such a direction as to swing the arms 19 and 19' downwardly as illustrated in Figure 4.

When the paper is in the correct position as illustrated in Figure 4, the arms 19 and 19' will move downwardly but will not strike the paper and, consequently, will not close the contacts 6 and 7. However, if the paper is in a wrong position, whether crumpled or straight, the shoe 18 will strike the same as illustrated in Figure 3 and the continued downward movement of the arms 19 and 19' will quickly cause a closing of the contacts 6 and 7 which in turn will quickly cause the opening of the circuit of motor 15. Preferably, the arms 19 and 19' are set 100 to move downwardly to the position shown in Figure 4 immediately after the rear edge of the paper has passed, but if desired, it could be set to move downwardly and then back immediately before the paper approached the contact members 6 and 7. In order to provide the desired adjustment so as to cause the arms 19 and 19' to move downwardly at the correct time, an auxiliary cam 43 is positioned adjacent cam 39, said auxiliary cam 43 being provided with an arc-shaped operating face 44 arranged on the body 45, which body is preferably provided with an aperture through which the shaft 42 extends. An arc-shaped slot 46 is arranged in body 45 for accommodating the bolt 47 carried by the cam 39, which bolt acts to lock the body 45 in any desired adjusted position in respect to cam 39.

When the parts are set as shown in Figure 2, the auxiliary cam 43 is not functioning but if it should be swung around towards the right until it overlaps the cam face 41 somewhat, it would then begin to function and cause the arms 19 and 19' to 120 125 130

remain elevated for a greater length of time. Where a large sheet is being fed by the machine, it is necessary to move the auxiliary cam 43 around so as to hold the arms 5 19 and 19' elevated until the rear edge has passed the contacts. After the cam 39 and the auxiliary cam 43 have been properly set, the machine will continue to function properly without any further attention or 10 consideration by the operator.

In case a sheet of paper should move through the machine at an angle or out of position, the contact shoe 18 will strike the same as shown in Figure 3, and the machine 15 will be immediately stopped. Quite often, the sheet which has caused the stoppage is not injured and may be straightened and the machine again started without the loss of a single sheet. Heretofore, the paper 20 would pile up at a given point until observed by the operator or until a sufficient amount had piled up to operate a swinging series of arms or grate as above mentioned. It will be thus noted that instead of piling 25 up a large amount of sheets which are very difficult to remove and which quite often throw off the various belts 4 and 26, a structure has been presented which will not affect the belts 4 and 26 or any other parts 30 of the machine in an objectionable manner but will immediately throw off the power when a sheet passes the contacts 6 and 7 out of proper time.

What we claim is:—

35 1. A choke detector for paper feeding machines, folding machines and the like, comprising a pair of electrical contacts normally spaced apart, a swinging arm adapted to move both of said contacts across the 40 path of the paper passing through the machine so as to engage the paper and be closed thereby in case the paper is out of its correct position, a rock shaft for actuating said arm, a system of levers, links and arms for 45 actuating said rock shaft, a cam for actuating said levers in one direction, and a spring for actuating the levers in the opposite direction.

50 2. A choke detector for paper feeding machines, paper folding machines and the like, comprising a swinging arm, a pair of normally spaced contacts carried by said

arm, and means for operating said arm, said means including a cam formed with an arc-shaped section and a cam face, and an auxiliary adjustable cam provided with an arc-shaped face adapted to be moved to in effect shorten and lengthen the arc-shaped surface of said cam. 55

3. A choke detector for paper feeding 60 machines, paper folding machines and the like provided with a plurality of substantially parallel feeding structures, comprising a swinging arm for each of the feeding structures, a pair of spaced electrical contacts carried by each arm, a rock shaft for supporting each of said arms, means for connecting the rock shafts so that they will operate in unison, power means for actuating one of said rock shafts so as to swing said 65 arms in proper time to the movement of paper through the machine, and means actuated by the closing of either of said contacts for shutting off power to said machine. 70

75 4. A choke detector for paper feeding machines, paper folding machines and the like provided with a feeding structure, comprising a swinging arm for the feeding structure, a pair of spaced electrical contacts carried by said arm, a rock shaft for supporting said arm, power means for actuating said rock shaft so as to swing said arm in proper time to the movement of paper through the machine, and means actuated 80 by the closing of said contacts for shutting off power to said machine. 85

5. A choke detector for folding machines and the like, comprising an arm, means for moving said arm back and forth over a given course, said course intersecting the path over which paper in said machine passes as the machine functions whereby if a sheet of paper is crossing said course when said arm is moving across said path said 90 arm will be arrested thereby, a pair of normally spaced contacts carried by said arm, said contacts being so positioned as to be closed by the action of said arm against said sheet of paper, and means actuated by the 95 closing of said contacts for stopping the machine. 100
